UNITED STATES PATENT OFFICE.

GEORGE LEONARD LAVINGTON, OF EAST HAM, ENGLAND, ASSIGNOR OF ONE-HALF
TO ARTHUR WILLIS, OF WINCHMORE HILL, ENGLAND.

LIFE-SAVING GUARD FOR STEAM AND MOTOR ROAD-VEHICLES.

1,386,938.

Specification of Letters Patent.

Patented Aug. 9, 1921.

Application filed June 25, 1920. Serial No. 391,742.

To all whom it may concern:

Be it known that I, GEORGE LEONARD LAVINGTON, a subject of the King of Great Britain and Ireland, and residing at 197 5 Milton avenue, East Ham, in the county of Essex, England, have invented certain new and useful Life-Saving Guards for Steam and Motor Road-Vehicles, of which the following is a specification.

10 The present invention relates to life saving devices adapted to be placed on the front of steam and motor driven road vehicles and the like.

Many such devices have been proposed, 15 but though differing greatly from the structural point of view they agree in the common purpose of pushing a prone person along in front of the vehicle, scooping him up or plowing him to one side, no matter whether 20 he has fallen before the collision or whether he has been knocked down by the vehicle.

In contrast to the above, the object of the 25 present invention is to provide a device which will prevent a person collided with by the front of the vehicle from falling to the ground and support him in such a manner that time is allowed for the vehicle to stop and so avoid running over the person who 30 has been struck by the guard.

35 In life saving devices for vehicles as heretofore constructed, no account has been taken of the desirability of preventing a person collided with from throwing his feet into the air and so falling directly to the ground.

According to the present invention the 40 feet of a person collided with are held by the guard and carried forward so that the fall of the person is controlled in such a manner that he falls upon the guard, which is so 45 designed that it retains and supports him, thus giving time for the vehicle to stop before the person can fall to the ground in front of the vehicle.

50 The invention consists in a guard formed of a suitable framework adapted to be attached to the front of a vehicle and having along its lower edge a device in advance of the framework adapted to push forward the feet of the person collided with and hold them in the lateral direction, thus causing the person to fall against the guard, which retains and supports him.

55 The invention further consists in constructing the guard in the form of a frame

with cross-bars situated in a plane slightly in front of the main frame, the cross-bars being placed in such a position that the arm or other portion of the person collided with naturally engages between these bars and the rear part of the frame, which retain him and prevent him falling to the ground for a period sufficient to allow the driver to stop the vehicle.

The invention further consists in the improved guard for fitting in front of a vehicle hereinafter described.

Referring to the accompanying drawings:—

Figure 1 is a front view of the guard, 70 while

Fig. 2 is a side elevation showing the guard in position in front of the vehicle.

Fig. 3 is a section showing a detail of the attachment, while

Fig. 4 is a section showing the method of attaching the device for catching the feet of the person collided with.

Fig. 5 is a section on the line 5—5, Fig. 3.

Fig. 6 is a plan view of a portion of the 80 guard shown in Figs. 1 and 2.

In carrying the invention into effect according to the form illustrated, there is provided a rectangular frame *a* over which are stretched wire cords or rods in two sets *b c*. 85 The plane of the sets *b* is a few inches in front of the sets *c* so that spaces are provided between the horizontal rods *b b b* and the vertical members *c* and *d*.

When fixed to the vehicle the frame may 90 take up an inclined position, as shown in Fig. 2, being held by suitable supporting arms *e*, or it may be vertical with the top curved back over the chassis.

Along the bottom edge of the frame there 95 is provided a forwardly projecting strip *f* of leather or the like scalloped along its front edge as shown at *g*, Figs. 1 and 6, to form recesses adapted to admit the ankle of the person collided with. By this means the 100 feet are prevented from movement in the lateral direction and pushed forward. The effect of this is that the person collided with falls backward on to the frame, and some 105 part of his body, for example his arm, will engage with the frame and may pass between the horizontal and vertical members thereof, the effect of this causing a delay to be imposed between the time of striking the person and the time at which he falls to the 110

ground, this delay allowing a sufficient period for the driver to stop the vehicle.

Any suitable device may be employed for securing the frame to the vehicle, but I prefer to employ the arrangement illustrated in Figs. 3 and 5. In this device a block *h* is fixed to the upright *c* of the frame, the block having in it two apertures *k* in which the ends of a spring loop *l* are inserted. The width of the loop is such that on lifting the end *m*, the sides of the loop come in contact with the inclines *n* on the block *h* so that the free ends *o o* of the loop are separated. By this means the end *p* of the arm *e* can be inserted in the vertical socket *r* in the block and when inserted can be retained by a loop *l* which on being pressed downward engages with one of the notches or apertures *s* in the part *p*. The guard is thus retained firmly on the arm *e*.

It will be seen that the frame may, if desired, be made reversible so that either the horizontal bars or vertical bars are in front.

Having now described my invention, what I claim as new, and desire to secure by Letters Patent is:—

1. A life saving guard for steam and motor road vehicles comprising in combination; a frame-work, means for attaching said frame-work to the front of the vehicle, and means projecting in the forward direction and having recesses along its edge, as and for the purpose described.

2. A life saving guard for steam and motor road vehicles comprising in combination; sets of bars at right angles forming a frame-work, means for attaching said frame-

work to the front of a vehicle, a strip of flexible material attached along the lower edge of said frame-work, scalloped recesses 40 in said strip, such recesses being of suitable width and at a suitable height above the ground to engage around the ankle of a person standing in front of the vehicle, as and for the purpose described.

3. A life saving guard for steam and motor road vehicles comprising in combination; sets of bars at right angles forming a frame-work, means for attaching said frame-work to the front of a vehicle, said frame-work comprising horizontal bars projecting in front of the main portion of the frame-work, a strip of flexible material attached along the lower edge of said frame-work, scalloped recesses 55 in said strip, such recesses being of suitable width and at a suitable height above the ground to engage around the ankle of a person standing in front of the vehicle, as and for the purpose described.

4. A life saving guard for steam and motor road vehicles comprising in combination; a frame-work adapted to be attached to the front of a vehicle, and means for attaching said frame-work including a block having inclined faces fixed to said frame-work, a spring loop carried by said block, said loop being adapted to be opened by its upward movement and closed by its downward movement, as and for the purpose described.

In testimony whereof I have signed my name to this specification.

GEORGE LEONARD LAVINGTON.
